COMBINED TABLE AND SEATS

Frank Giberson, South Lyon, Mich.

Application June 27, 1946, Serial No. 679,692

6 Claims. (Cl. 155—124)

1

This invention relates to tables and particularly tables designed for outdoor use and commonly termed picnic tables.

Picnic tables are generally of a size to accommodate a considerable number of persons and usually comprise permanently attached seats. Such tables, as heretofore constructed, are too bulky to be put in storage through the winter, and their exposure through the winter months tends to greatly shorten their useful life. Such tables have also been awkward to handle and have required too much space to permit their shipment at reasonable cost.

It is an object of the invention to adapt a picnic table to be readily disassembled into units suited for compact storage and convenient handling and shipping, without unduly increasing manufacturing costs as compared to present practices.

Another object is to produce a "knock-down" type of outdoor table that will be as strong, if not stronger, than tables now built for a like purpose of inseparable parts.

These and various other objects are attained by the construction hereinafter described and illustrated in the accompanying drawings, wherein:

Fig. 1 is a top plan view of my improved table.

Fig. 2 is a side elevational view of the same.

Fig. 3 is a view of the table in end elevation.

Fig. 4 is a bottom view of the table top, as a disassembled unit.

Fig. 5 is a vertical sectional detail, taken on the line 5—5 of Fig. 3, showing a releasable interlock between the top and an end frame of the table.

Fig. 6 is a vertical sectional detail taken on the line 6—6 of Fig. 3, showing a releasable interlock between a seat-forming plank and an end frame.

Fig. 7 is an enlarged view of a portion of Fig. 2 showing tensioning means for a tie rod.

In these views, the reference character 1 designates a table top formed of planks in side-by-side relation, rigidly interconnected by two heavy iron straps 2 extending across the end portions of said top, and secured to the under faces of the individual planks by screws 3 (Fig. 4). Said top seats on a pair of end frames, each comprising a pair of heavy legs 4, a bridging joist 5 surmounting such legs, and a bracing joist 6 mortised into the mid portions of the legs. A bolt 7 and nut 7a rigidly secure each leg to the joist 5 and the joist 6 is rigidly mounted on the legs by bolts 8 and nuts 8a. Securely driven into each end portion of each joist 5 is a pin 9, preferably

2

approximately vertical, the lower portion of these pins extending snugly into the legs, whereby such pins supplement the bolts in maintaining the end frame assemblies. The pins 9 have flattened heads 10 spaced slightly above the joists 5 to enter recesses 11 in the under face of the table top, such recesses overlying the straps 2 and being elongated from each strap toward the adjacent table end to allow the heads 10 to enter the recesses. The heads 10 of the pins of each end frame project toward the opposite end frame so that said heads may be wedged in the recesses 11 above the straps 2 by shifting the end frames slightly toward each other, after initial insertion 15 of the heads in the recesses. Thus, when the table is assembled, the straps 2 are interposed between the inner margins of the joists 5 and the top 1 establishing a desirable slight outward pitch, from top to bottom of the end frames, 20 such as to increase the space available beneath the table.

The joists 6 project sufficiently beyond the legs to seat bench-forming planks 12 extending at each side of the table. The planks 12 may be 25 disassembled from the end frames, similarly to the top 1, each plank having underlying iron cross straps 13 on its end portions and having a recess 14 above each strap elongated beyond the strap toward the adjacent plank extremity. 30 Each end portion of each joist 6 carries a substantially vertical bolt 15 held in place by a nut 15a, the heads 16 of these bolts being spaced slightly above the joists 6 to enter the recesses 14, said heads on the two end frames being elongated toward each other and flattened to wedge 35 in said recesses above the straps 13, when the end frames are shifted slightly toward each other. To each bolt 15 there is welded a collar 17 slightly below the head 16 to resist the downward 40 stress imposed by the nut 15a and assure the desired upward spacing of such head from the corresponding joist 6.

To securely maintain the described table assembly, a pair of elongated rods 18 establish a 45 releasable connection between the joist 5 of each end frame and the joist 6 of the opposite frame, such rods being thus diagonally crossed, as best appears in Fig. 2. It is preferred to dispose these rods at least approximately in the medial vertical 50 longitudinal plane of the table so that they avoid interference with use of the benches. The upper ends of the rods form hooks 19 to detachably engage staples or the like driven in the joists 5, and latch arms 20 pivoted to the lower ends of 55 the rods afford leverage for tensioning the rods

in engaging them with short lengths of chain 21 secured to the joists 6. When said latch arms are transverse to the rods, as indicated in dash lines in Fig. 7, they may be slipped through any desired links of the chains 21, and a considerable tensional stress may then be applied to the rods and chains by swinging the latch arms to approximate parallelism with the rods. The tensioning positions of the latch arms may be maintained by so pivoting rings 22 on the rods that they may be swung across the arm extremities to encircle or release the arms.

Since the top, end frames, bench planks, and tensioning rods of the described table are separable units, it is evident that the problem of winter storage is greatly simplified as compared to a permanent assembly. The unit construction further greatly facilitates transportation to and from a place of storage, and renders it feasible to ship the table in a sufficiently compact form to avoid prohibitive freight rates.

What I claim is:

1. A table comprising a top, formed by a plurality of elongated members in side-by-side relation, a pair of cross bars secured to the end portions of the top, therebeneath, fastenings securing said bars to the several elongated members and holding such members in assembly, a pair of end frames for seating said top, anchoring projections rigidly mounted on each end frame engageable above said cross bars to interlock the top and end frames, and releasable connections between the end frames normally establishing and maintaining the interlocking relation of the top and end frames, the top having recesses in its bottom face overlying said cross bars and extending beyond the cross bars toward the ends of the top to admit said projections, such projections being spaced above the end frame to enter said recesses.

2. A table as set forth in claim 1, said releasable connections extending approximately in the medial vertical longitudinal plane of the table from the top portion of each end frame to the mid portion of the other end frame.

3. A table comprising a top, a pair of end frames for seating the top, each end frame including a cross brace having end portions projecting beyond such frame, and a pair of seats at the sides of said table supported on said projecting end portions, the top and seats having cross bars secured to their under faces, projections on the end frames engageable above said cross bars by movement of the end frames toward each other, and detachable means for stress-

ing the end frames toward each other to maintain said projections above the cross bars.

4. A table as set forth in claim 3, said detachable means being substantially equidistant from said seats.

5. A table comprising a pair of end frames, each including a cross brace having end portions projecting beyond such frame, a top seated on and bridged across said end frames, a pair of seats at opposite sides of said top, supported on and bridged across the end portions of the cross braces, a cross bar secured to the under face of each end portion of each seat, upward projections on the end frames engageable above said cross bars by movement of the end frames toward each other, an elongated tie member interconnecting the end frames and substantially equidistant from the seats, and means for regularly tensioning said tie member.
- 10 6. A table member comprising a top, a pair of cross bars respectively secured to and beneath the respective end portions of the top, a pair of end frames for seating the top, each such frame including a pair of legs and a member bridged
- 15 across such legs, pins downwardly driven into the bridging members and connecting the bridging members to the legs, and formed with heads engageable above said cross bars to lock the top on the end frames, and releasable connections between the end frames, holding said heads in their locking positions above the cross bars.

FRANK GIBERSON.
